US0D1024540S

(12) **United States Design Patent** (10) **Patent No.:** **US D1,024,540 S**
(45) **Date of Patent:** **** Apr. 30, 2024**

(54) **BRAIDING DEVICE**

(71) Applicant: **LaTicia Scott-Suesberry**, Killeen, TX (US)

(72) Inventor: **LaTicia Scott-Suesberry**, Killeen, TX (US)

(73) Assignee: **LaTicia Scott Suesberry**, Killeen, TX (US)

(**) Term: **15 Years**

(21) Appl. No.: **29/798,615**

(22) Filed: **Jul. 9, 2021**

(51) **LOC (14) Cl.** **28-03**

(52) **U.S. Cl.**

USPC **D28/10; D3/25; D6/512**

(58) **Field of Classification Search**

USPC D3/18-29; D28/10, 7, 65, 67, 17, 73; D15/72, 78, 127, 139, 73, 76, 77, 66; D8/80, 83, 98, 107, 303, 312, 14, 16, D8/354, 367, 499; D7/213, 649, 669; D19/55, 90, 163; D24/130, 133, 146; D4/122; D21/698, 780; D11/47, 200; D6/552, 642, 671.1, 672, 680.2
